2,638,537

RAILWAY SWITCH CONTROLLING APPARATUS

Harry C. Van Tassel, Edgewood, Pa., assignor to
Westinghouse Air Brake Company, a corpora-
tion of Pennsylvania

Application October 14, 1950, Serial No. 190,182

8 Claims. (Cl. 246—219)

1

My invention relates to apparatus for the control of a railway track switch, and more particularly to apparatus for enabling a track switch to be operated by power by remote control under emergency conditions, such as when a detector track relay, the release of which is normally relied upon to prevent the operation of the switch under a train, is released due to a fault.

Emergency release means are known, as shown for example in Letters Patent of the United States No. 2,368,766, issued February 6, 1945, to Ronald A. McCann, for Railway Traffic Controlling Apparatus, in which the manipulation of an emergency lever or push button by an operator in a control tower sets a time element device into operation which after a suitable time interval enables the switch to be operated at least once even though the controlling track relay is released. Usually the control machine is close enough to any switch in the controlled territory to enable the operator, by looking at the tracks, to assure himself that there is no train in the switch section at the time the emergency operation is to be made. In addition, the emergency operation is conventionally protected by approach locking relays which are energized only when all of the signals which govern train movements over the switch are properly at stop, and these relays must be energized to permit the switch to be operated under the emergency condition referred to the same as in the normal operation of the system.

The principal object of my invention is to provide apparatus of this general character which includes additional safeguards, enabling the emergency operation of a switch to be effected safely and economically by remote control, when the control machine is such a distance from the switch, several miles for example, that the condition of the tracks cannot be observed by the operator. For this purpose I provide a form of "dual control" by which the continued pressing of a button or key at the switch location is necessary, to enable the control operator to initiate the emergency control and to operate the switch thereby, this key being held closed by a trainman or other employee who is in a position to see whether or not it is proper to move the switch.

A further novel feature of my invention is the provision of a communication circuit of the coded type for the remote control of the time element device by the operator, which functions in such a manner that a release of the locking can be obtained only in the absence of crosses or foreign current in the circuit connection of the tower

2

with the switch location. This is of importance from the standpoint of cost in view of the distances involved, since otherwise a more expensive construction would be needed in order to properly protect this circuit from the effects of line circuit faults.

The mode of operation of the emergency apparatus of my invention is briefly as follows: The operator at the control office, desiring to change the position of the track switch at a time when, for example, the continued lighting of a track occupancy lamp on his track diagram indicates a track circuit failure, will instruct an employee at the switch location, by telephone or otherwise, to close the emergency key if he observes that the switch section is not occupied, and to hold the key closed until the switch responds. The operator also places the switch lever for the switch in the position designating the direction he wishes the switch to move, and then transmits a series of impulses over the communication circuit above referred to, by the repeated operation of an emergency push button associated with the switch lever.

After the reception of a predetermined number of impulses at the switch location, such as fifteen, for example, while the emergency key is held closed, a time element device closes contacts which bridge those controlled by the track relay, thus energizing a switch locking relay and thereby enabling the switch to assume the position designated by its switch lever.

A switch correspondence relay becomes energized when the switch assumes its new position, and this relay releases the time element device, thereby placing the switch locking relay again under the control of the track relay.

The apparatus is thus so arranged that the closing of the key at the switch location ceases to be effective when the switch arrives at its new position, each operation of the emergency apparatus being effective for only one change in the position of the switch.

The apparatus of my invention is particularly adapted, but not limited, to use with interlocking systems of the route control type, such as is shown, for example, in Letters Patent of the United States No. 2,301,297, issued November 10, 1942, to Lloyd V. Lewis, for Railway Traffic Controlling Apparatus. In such systems, as well as in others not employing the route principle of control, it is the practice to provide a system of cascade connected directional route locking relays such as the relays ES and WS shown in Fig. 1F of this Lewis patent, for the control of

the switch locking. These relays are governed by the approach locking relays and arranged to unlock each switch of a route to enable it to be operated as soon as the corresponding detector section is vacated by a train. Each directional route relay is governed by the detector track relay for the corresponding section and so will fail to pick up in the event the track relay remains released due to a fault. In this case the failure of the track relay in one section may prevent the operation of a switch in another section.

This difficulty is overcome in accordance with my invention by arranging the circuits in such a manner as to enable a switch to be operated by the emergency apparatus in the event a route relay which controls the switch is released, but only if the approach locking relay which governs such route relay is properly energized.

I shall describe one form of apparatus embodying my invention, and shall then point out the novel features thereof in claims.

In the accompanying drawing, a track plan is shown which represents a typical portion of an interlocked track layout comprising a detector track section **1T** having therein a power operated track switch **W**, an adjoining track section **3T**, and three signals **4R**, **2R** and **2L** for governing the movement of traffic over the switch. Each track section is provided with a detector track circuit having a track battery **TB** and a normally energized track relay **1TR** or **3TR**, and each signal controls an approach locking relay **4RAS**, **2RAS** or **2LAS**, which, as indicated diagrammatically by a dotted line connection to a circuit controller adjacent the symbol for the associated signal, is energized only when the signal is properly at stop. These relays may be governed like the relays **AS** in Fig. 1F of the Lewis patent referred to.

It is to be assumed that the track switch and signals shown are controllable from a distant point, designated as the "Office" on the drawing, by a route control system of the type shown in this Lewis patent. In the normal operation of the system, the switch **W** is governed by route selector relays **NR** and **RR** as in Fig. 2C of this patent, and under emergency conditions by an individual switch lever **SW** corresponding to lever **1W** of the patent.

As shown herein, the switch is governed by normal and reverse switch control relays **NWR** and **RWR** controlled from the office over the line wires **10** and **11** in such manner that they reflect the positions of relays **NR** and **RR** or of lever **SW**. The relays **NWR** and **RWR** are of the biased neutral-type, and respond like an ordinary neutral relay to current which flows in a particular direction, as indicated by an arrow, but are non-responsive to current flowing in the opposite direction. Relay **NWR** is picked up either when relay **NR** is energized or when lever **SW** is moved to the left, for operating the switch from reverse to normal, by current which flows from the positive terminal **B1** of the office battery over line **10** and returns over line **11** to the center battery terminal **C**. Relay **RWR** is picked up either when relay **RR** is energized or when lever **SW** is moved to the right to reverse the switch by current which flows from terminal **C** over line **11** and returns over line **10** to the negative terminal **N1** of the office battery.

A local battery having terminals designated **B** and **N**, respectively, is provided for energizing the various local circuits at the switch location. The switch **W** is operated by a switch machine of a conventional type, having an electric motor **M**.

which is arranged to be energized to move the switch to its normal or reverse position by the operation of a normal or reverse switch operating relay **NWS** or **RWS**, and the latter, jointly with a circuit controller, actuated by the switch machine, control normal and reverse switch correspondence relays **NWC** and **RWC**, which like those shown in Fig. 1F of the Lewis patent, indicate when the switch occupies the position designated by the switch operating relays.

Relays **NWS** and **RWS** are controllable by relays **NWR** and **RWR** only under proper traffic conditions as reflected by a switch locking relay **LS** which is like those shown in Figs. 1C and 2C of this patent.

As typical of the directional route locking above referred to, a directional route relay **1ES** is shown herein having a pickup circuit which may be traced from terminal **B** over contacts **a** of relays **4RAS** and **2RAS** in series, and thence over contacts **a** of relays **3TR** and **NWC** in parallel, and over contact **a** of relay **1TR** through relay **1ES** to terminal **N**. Relay **1ES** is normally held energized over a stick circuit which includes the contacts **a** of relays **4RAS**, **2RAS**, and **1ES** only.

The switch locking relay **LS** has a pickup circuit which may be traced from terminal **B** at the normally closed contact of an emergency key **EPB** over front contacts **b** of relays **1ES**, **1TR**, and **2LAS** through relay **LS** to terminal **N** over back contacts **a** of relays **RWR** and **NWR**. The last mentioned contacts are closed only when lever **SW** is in its center position and relays **NR** and **RR** are deenergized, as shown, and when relay **LS** picks up, are bridged by its front contact **a** to complete a stick circuit for relay **LS**.

The apparatus so far described is typical of that conventionally provided in systems of this character. The additional apparatus which is required to apply my invention to the system comprises the time element device **TER** shown at the right, the emergency key **EPB** at the switch location, and the emergency button **EB** at the office. An additional line wire **12** is also shown, but this is not always needed, and optionally the circuit controlled by button **EB** may be superimposed upon some existing communication circuit.

The time element device **TER** is a modification of that described and claimed in Letters Patent of the United States No. 1,966,965, issued July 17, 1934, to Branko Lazich and Harry E. Ashworth, for Electrical Relays. This device is illustrated herein in diagrammatic form but with reference characters similar to those for corresponding elements in the patent; the principal difference being that whereas in the patent the device is controlled by a unitary magnet structure, it is herein controlled by two separate magnets, a drive magnet **DM**, and a control magnet **CM**.

This device is essentially an impulse counter comprising a shaft **26** adapted to rotate in suitable bearings, not shown, having solidly mounted thereon a ratchet wheel **41** and a pinion **43**. Also mounted on shaft **26**, but freely rotatable thereon, there is a gravity biased contact arm **F**, and a gear wheel **50** to which is attached a clutch wheel **51**. A countershaft **45** is mounted on arm **F** so that it is rotatable about its own axis as well as that of shaft **26**, and to shaft **45** is attached a gear wheel **44** and a pinion **49**. The gear wheel **44** meshes with the pinion **43** attached to the ratchet wheel, and the pinion **49** meshes with the gear wheel **50** attached to the clutch wheel.

When the clutch is free, the effect of gravity

is to rotate the assembly as a whole counterclockwise to the normal position shown, this being indicated by the closing of a check contact D connected to the contact arm F.

When the drive magnet DM is periodically energized, a pawl 39 attached to its armature drives the ratchet wheel 41 and pinion 43 step by step in the counterclockwise direction, and if the clutch is free, the gearing rotates the clutch wheel 51 counterclockwise at reduced speed, arm F remaining in its normal position.

If the control magnet CM is energized, a brake shoe 52 attached to its armature presses against the clutch wheel 51 and prevents its rotation, and in this case the step by step rotation of the ratchet wheel acting through the gearing causes member F to rotate clockwise on shaft 26.

Attached to the arm F is a segment 60 which may be adjusted to close two contacts 14 and 15 connected thereto after a selected number of operations of the drive magnet DM and to also open a contact 13 which, as shown, is included in the circuit for the drive magnet and serves to prevent its further operation.

Arm F and the adjustable segment 60 are held in any position to which they are moved by magnet DM as long as magnet CM remains energized for the reason that, when the clutch wheel is held stationary, the counterclockwise rotation of arm F is possible only if the ratchet wheel rotates in the clockwise direction, and this is prevented by the action of a holding pawl 42.

This device may be operated by supplying impulses to magnet DM which are generated by a pendulum relay or the like so that they recur at a predetermined fixed rate, but for its application to my invention it is simpler and equally effective to supply the impulses manually by the repeated operation of the push button EB.

Essentially, this device is used herein as a code responsive device or selector and my invention is not limited to this particular device but may alternatively employ a selector of a different type, such as one selectively responsive to impulses arranged in some distinctive code pattern or arranged in groups corresponding to the digits of a number, for example.

I shall now describe the operation of the system under different assumed conditions, assuming first that switch W has been reversed, in which case relays NWS and NWC are released and relays RWS and RWC are picked up, and that signal 4R has been cleared, thereby releasing in turn relays 4RAS, IES, and LS. The release of relay LS, by opening its contacts b and c in the circuits for the switch operating relays, locks switch W in its last operated position, which in this case is the reverse position. When a train governed by signal 4R enters section 3T, the signal returns automatically to stop and relay 4RAS is reenergized, as explained in the hereinbefore mentioned Lewis patent. Contact a of relay NWC being open, relay IES is held released after relay 4RAS picks up, first by relay 3TR, and then by relay 1TR, and so picks up only when the train vacates section 1T.

Assuming next that switch W has been restored to normal, relays NWS and NWC being energized and relays RWS and RWC released, and that signal 2R has been cleared, thereby releasing relay 2RAS. In this case, relays IES and LS are released by relay 2RAS, and maintained released while section 1T is occupied by relay 1TR. Contact a of relay NWC is now closed and prevents the control of relay IES by relay 3TR.

When signal 2L is cleared for an opposing train movement over switch W normal or reverse, relay IES remains energized and relay LS is held released, until the signal is put to stop and section 1T is vacated, by relays 2LAS and 1T.

It will be seen that in each case a failure of the detector track relay 1TR to pick up will prevent the operation of the switch by opening its contact b in the circuit for relay LS, and that this circuit will be open at contact b of relay IES in the event of a fault in the circuit for that relay, or if relay 3TR fails to pick up following a train movement over the route governed by signal 4R.

Assuming that the operator desires to operate switch W from normal to reverse at a time when relay LS is deenergized due to the release of relay 1TR or IES, he will move the switch lever to its right-hand position and thereby energize relay RWR, which, by closing its front contacts b and c will prepare circuits for the reverse switch operating relay RWS and for magnet CM of the device TER.

Under this condition relay RWC stands released, and with relay RWR energized, the pressing of the emergency key EPB at the switch location completes a circuit from terminal B over its normally open contact and the front contacts c of the approach locking relays 2LAS, 2RAS, and 4RAS, thence over contacts b of relays RWR and RWC through magnet CM to terminal N at the normally closed check contact D. Magnet CM then picks up and presses the brake shoe 52 against wheel 51 to prevent its rotation, closes its contact a in order to maintain its circuit closed after contact D opens, and closes its contact b to prepare the circuit for magnet DM.

The operator now presses the emergency button repeatedly each time completing a circuit from the office battery terminal B1 over back contacts of the route selector relays NR and RR, the contact of button EB, line wire 12, the winding of magnet DM, contact b of magnet CM, contact 13 and line wire 11 to terminal C of the office battery. After the specified number of operations of magnet DM, fifteen, for example, contacts 14 and 15 close and contact 13 opens. Contact 14 connects terminal B to one terminal of relay LS over contact b of relay 2LAS, bridging the open contact b of relay 1TR or IES, and contact 15 connects terminal N to the other terminal of relay LS, bridging the back contacts a of relays NWR and RWR, contact a of relay RWR now being open. Relay LS therefore picks up and completes the pickup circuit for relay RWS, which assumes its energized position and by opening its back contact b, releases relay NWS, which in turn releases relay NWC and completes a holding circuit for relay RWS.

The closing of contacts d and e of relay RWS completes a circuit for motor M to operate the switch to reverse, and then relay RWC picks up over a circuit closed by the switch machine in the reverse position which includes contact c of relay RWS.

The opening of back contact b of relay RWC opens the circuit for magnet CM which becomes deenergized to release the clutch and permit the contact arm F to return to its normal position and to close contact D.

Switch W may be restored to its normal position, as shown, by a similar sequence of operations. The movement of lever SW to its left-hand position energizes the normal switch control relay NWR, contact b of which prepares a circuit for magnet CM which is opened at contact

tact *b* of relay NWC when the switch assumes the normal position.

It will be seen that the position of the emergency key is checked by including its normally closed contact in the circuit by which relay LS is energized in normal operation, and since the circuit controlled by button EB includes back contacts of relays NR and RR, the emergency operation of the switch cannot be effected by route control, but requires the use of the individual switch lever SW.

It is to be understood that the relay IES may be one of a chain of route relays connected as shown in Fig. 1F of the Lewis patent or otherwise to conform to the route established over switch W, and that when the routes include additional switches at the right, a corresponding relay designated IWS would be provided having a front contact in the circuit for relay LS, and in that case the circuit for magnet CM would include a front contact of each approach locking relay which controls the relay IWS as well as of those which control relay IES, as shown. My invention therefore enables the emergency operation of the switch to be effected in the event of the failure of the track relay or route relay for any section of the established route over the switch, and not merely those for the section which includes the switch.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In a system for controlling a railway track switch from a remote point, said system having signals for governing the movement of traffic over the track which includes the switch and having one or more track relays the energization of which indicates that said track is not occupied by a train, said system also having switch operating means controllable from said remote point when said signals are at stop to change the position of the switch, said operating means being normally controllable only after said track relay or relays become energized following the movement of a train over the switch; emergency apparatus for enabling said switch operating means to be actuated irrespective of the condition of the track relays, comprising a switch lever and an emergency button at said remote point, a code responsive selector at the switch location having a drive magnet, a control magnet, and contacts which move from a normal at rest position to a closed position when the control magnet is energized and a code signal is supplied to the drive magnet, an emergency key at the switch location; a circuit for energizing said control magnet which is closed when said emergency key is operated, provided said signals are at stop but only if said switch lever and the track switch are in noncorresponding positions, a circuit controllable by said emergency button effective only so long as said control magnet is maintained energized by the operation of said emergency key for supplying a code signal to said drive magnet, and means controlled by the contacts of said selector for actuating said switch operating means when said code signal is fully received, to thereby cause the switch to assume a position corresponding to that of said switch lever.

2. Emergency switch controlling apparatus of the type recited in claim 1, in which the selector contacts are biased by gravity to said normal at rest position and are operated step-by-step to said closed position in response to the reception of a series of impulses received by the drive magnet during the time said control magnet is energized, and the selector is arranged to actuate said switch operating means when its contacts assume their closed position irrespective of the condition of said track relay or relays but only if the signals which govern traffic movements over the switch are at stop.

3. Emergency switch controlling apparatus of the type recited in claim 1, in which the circuit for the control magnet includes a checking contact closed by the selector only in its normal at rest position, and a contact connected in multiple therewith which is closed by the control magnet in its energized position.

4. Emergency switch controlling apparatus of the type recited in claim 1 in which the selector is operable step by step from its normal at rest position by the repeated operation of said emergency button and arrives at its circuit closing position after a predetermined number of operations of said emergency button provided they occur while the emergency key at the switch location is held closed.

5. In apparatus for the remote control of a power operated track switch located in a detector section of railway track having a normally energized track relay for indicating the condition of occupancy of said section, signals for governing the movement of traffic through said section, approach locking relays which when energized indicate that the signals are at stop and that it is proper to operate the switch provided the track relay is also energized, said switch having operating means normally controllable from a remote point only when said approach locking relays and track relay are energized, for enabling the position of the switch to be changed; the combination of the foregoing with emergency means for rendering said switch operating means controllable from said remote point when said track relay is released comprising, a time element device having a drive magnet, a control magnet, and contacts which move from a normal at rest position to a closed position when a predetermined number of impulses are supplied to said drive magnet, only if said control magnet is energized, an emergency key at the switch location, an emergency button at said remote point, a circuit controllable by said button for supplying impulses to said drive magnet to enable said contacts to be closed by remote control when said control magnet is energized, a circuit including the contacts of said time element device for rendering said switch operating means controllable from said remote point irrespective of the condition of said track relay, provided said approach locking relays are energized, and pickup and stick circuits for said control magnet closed only when said emergency key is held closed and said approach locking relays are energized said pickup circuit including a contact closed only when said time element device is in said normal at rest position.

6. In remote control apparatus having emergency means for controlling a track switch associated therewith as recited in claim 5, in which the emergency means is arranged so that the circuit for the control magnet is opened by the operation of the switch when it assumes the position designated by the switch operating means,

whereby the time element device is returned to its normal at rest position as soon as the switch operation initiated thereby is completed.

7. In apparatus for the remote control of a power operated track switch located in a detector section of railway track having a normally energized track relay for indicating the condition of occupancy of said section, signals for governing the movement of traffic through said section, approach locking relays which when energized indicate that the signals are at stop and that it is proper to operate the switch provided the track relay is also energized, said switch having operating means normally controllable from a remote point only when said approach locking relays and track relay are energized, for enabling the position of the switch to be changed; the combination of the foregoing with emergency means for rendering said switch operating means controllable from said remote point when said track relay is released comprising a control magnet, a drive magnet, and a step by step device operable from a normal at rest position to a circuit-closing position in response to a predetermined number of operations of said drive magnet provided they occur when the control magnet is energized, a circuit for said control magnet including a manually operable key at the switch location and contacts closed only when said approach locking relays are energized, a circuit for said drive magnet including a manually operable contact at said remote point, and means controlled by said device when it assumes its circuit-closing position in response to a predetermined number of operations of said manually operable contact for enabling said switch operating means to be controlled from said remote point irrespective of the condition of said track relay.

8. In combination with a detector section of railway track including a power operated track switch, a normally energized track relay for indicating the condition of occupancy of said section, signals for governing the movement of

traffic through said section, approach locking relays which when energized indicate that the signals are at stop and that it is proper to operate the switch provided the track relay is also energized, a normally energized switch locking relay which normally reflects the energized condition of said approach locking relays and of said track relay, a manually operable switch lever at a remote point, switch operating means controllable by said switch lever only when said switch locking relay is energized to enable the position of the switch to be changed; emergency means for rendering said switch operating means controllable by said lever comprising a time element device having a drive magnet, a control magnet, and contacts which move from a normal position to a closed position when the control magnet is energized and a predetermined number of impulses are supplied to the drive magnet, means controlled by the contacts of said time element device when operated for energizing said switch locking relay provided only said approach locking relays are energized, means for maintaining said control magnet energized to render said time element device effective comprising an emergency key at the switch location, means for operating said drive magnet comprising an emergency button at the location of said lever, and means for initially energizing said control magnet effective only if the contacts of said time element device are in their normal position when said emergency key is closed.

HARRY C. VAN TASSEL.
